(57) **CLAIM**

The ornamental design for a platform with cushion, as shown and described.

DESCRIPTION

FIG. 1 is a perspective view of the platform with cushion; FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken line portions of the drawings are included to show portions of the article that form no part of the claimed design.

5/17
The claimed design is shown with symbolic breaks. The appearance of any portion of the platform with cushion between the symbolic break lines forms no part of the claimed design.

1 Claim, 5 Drawing Sheets

FIG. 1

FIG. 2**FIG. 3**

FIG. 4**FIG. 5**

FIG. 6

FIG. 7
